UNITED STATES PATENT OFFICE.

JOSEPH E. CRAIG, OF GARY, INDIANA.

COMBINED DENTAL MIRROR AND SYRINGE.

1,352,789.

Specification of Letters Patent. Patented Sept. 14, 1920.

Application filed May 15, 1920. Serial No. 381,636.

To all whom it may concern:

Be it known that I, JOSEPH E. CRAIG, a citizen of the United States, residing at Gary, in the county of Lake and State of Indiana, have invented certain new and useful Improvements in a Combined Dental Mirror and Syringe, of which the following is a specification.

This invention relates to improvements in mouth mirrors designed for use by dentists, physicians, and the like, and has for its object to provide a mirror of the class, which is adjustably supported by a tubular body or handle. A further object is to combine with the mirror and its support a syringe or fountain bulb, which is attached to one end of the body and carries a supply of water adapted to flow through the body by gravity, and which may be directed, by the aid of the mirror, in the form of a spray to different parts of the mouth of a patient, for washing and cooling the teeth at intervals during the dental operations. And a further object is to provide novel and simple means for admitting atmospheric pressure to the water-bulb for displacing the water, as well as simple means for controlling the admission of the air.

I attain these objects by the means set forth in the detailed description which follows, and as illustrated by the accompanying drawing, in which—

Figure 1 is a central longitudinal section: showing by full lines the construction and arrangement of the various parts; the dotted lines showing the adjustment of the mirror and its support. Fig. 2 is a perspective view of the mirror and the nozzle.

In the drawing, 2 is the main body or handle of the device, preferably comprising a tube which is bent at 2' intermediate its ends to facilitate the handling and operation of the device. The ends of the body are open, and the top end is provided with an annular bead 2^a which is inserted in and is gripped by the neck 3' of an elastic bulb 3. The bulb 3 is intended to be filled, or partially filled with water, or with a suitable liquid disinfectant 4, for use in washing out a patient's mouth, and for cooling off a tooth made hot during the usual grinding or cleansing operations. The support for the mirror is in the nature of a syringe and the tubular body 2 is preferably so proportioned to the bulb 3 as to prevent the accidental escape of the water. The water con-

tained in the bulb 3 may be displaced by the compressing of the bulb, in a well-known manner, but I prefer to expel the water in a novel, simple and convenient manner, by admitting air at atmospheric pressure to the bulb, preferably at or near the top above the level of the water 4, as at 4'. To accomplish this, I dispose a relatively small caliber tube 5 in the top-end portion of the body 2. The lower end of the air-tube 5 is bent and projects a short distance through the wall of the body, as at 5', while the opposite end of said tube extends concentrically inside the bulb 3 and terminates a short distance from the inner top surface of the bulb (see Fig. 1). In order that the inflow of the air to the bulb 3 may at all times be completely under the control of the operator, I employ a valve consisting of a lever 6, which is pivoted at 7' to a collar 7, the latter being supported by the body 2, preferably below the bend 2'. One end 6' of the lever is fitted with a compressible facing 6^a, which normally seals the lower end of the air tube. The lever 6 is held in the position shown in Fig. 1 for closing the air tube, by the tension of a cushion spring 8 which is disposed between the pivot 7' and the free end of the lever. Whenever the operator desires to wash out or cool off a tooth, he depresses the free end of the lever 6. This moves the end 6' away from the mouth of the tube 5 and admits the air at atmospheric pressure to the bulb 3, which forces the water through the handle 2. By this construction and arrangement, the operator may effect the expelling of all, or a portion of the water at will.

9 represents the mirror, which is mounted rigidly upon bracket 9', to which are secured spaced rings or collars 9^a which encircle the reduced intermediate portion 10' of a tubular nozzle 10. The rings 9^a are in frictional engagement with the nozzle, and the mirror 9 may be rotated or moved longitudinally on the nozzle, for changing its position, as shown by the full and dotted lines in Fig. 1. One end 10^a of the nozzle is expanded, and preferably telescopes the lower end of the body 2, as shown. The nozzle is also preferably held in place in the body by friction, so as to permit the nozzle to be detached for sterilizing the instrument. By this construction and arrangement of the parts, the nozzle 10 may also be rotated and set in different positions relatively to the body, as shown

- by dotted lines in Fig. 1. The free end of the nozzle 10 comprises a small bulb 10^b, which is perforated at 10^c, for producing a relatively fine spray of the water, whenever the operator manipulates the valve 6. The bulb 10^b preferably extends beyond the mirror 9, so that the spray may be directed, by the aid of the mirror, into the cavity of a tooth without interference from the mirror.
- 10 The bulb 10^b serves to prevent the mirror from becoming detached from the nozzle. When the mirror is held horizontally, the bend in the body 2 insures the free gravitation of the water by the opening of the 15 valve 6.

Having thus described my invention, what I claim as new and desire to secure by Letters Patent, is—

1. In a dental syringe, a bent tubular body open at its ends, a bulb mounted on one 20 end of the body, an adjustable nozzle mounted on the opposite end of the body, an air-tube disposed in said body and having one end extending into the bulb, the other end 25 of said tube projecting through the wall of the body, and a tension valve for controlling the flow of air through said tube.
2. In a dental syringe, a bent tubular body open at its ends, an elastic bulb mounted 30 on one end of said body, an air-tube disposed partially in said bulb and partially in said body, a valve for controlling the admission of air to said bulb, and a detachable nozzle 35 adjustably connected to the opposite end of

the body adapted to adjustably support a 35 mouth mirror, said nozzle having a spray-bulb at its free end for preventing the detachment of the mirror.

3. The combination with a mirror mounted on a bracket, of a bent tubular body, an elastic bulb mounted on one end of the body, an air-pipe disposed in the body, one end of said pipe projecting through the wall of the body, the other end extending concentrically in said bulb, a valve for controlling the admission of air through said pipe into said bulb, and a nozzle telescoping the opposite end of the body having a reduced portion upon which said bracket is slidable and rotatable and having a perforated bulb beyond 50 said bracket.

4. The combination with a mirror mounted on a bracket, of a bent tubular body having open ends, a nozzle telescoping one end of the body and having a reduced portion 55 for adjustably supporting said bracket, an elastic water-bulb mounted on the opposite end of the body, an air-tube disposed inside said body, one end thereof projecting through the wall of the body, the other end 60 extending into the water-bulb adapted to admit air for expelling the contents of the bulb, and a spring-controlled valve mounted on the body and normally closing one end of said air-tube.

In testimony whereof I affix my signature.

JOSEPH E. CRAIG.
